UNITED STATES PATENT OFFICE.

WILLIAM C. GOSS, OF MINNEAPOLIS, MINNESOTA.

LOCKING-SLIDE FASTENER.

1,320,385.

Specification of Letters Patent.

Patented Nov. 4, 1919.

Application filed April 1, 1918. Serial No. 226,082.

To all whom it may concern:

Be it known that I, WILLIAM C. Goss, a citizen of the United States, residing at Minneapolis, in the county of Hennepin and 5 State of Minnesota, have invented certain new and useful Improvements in Locking-Slide Fasteners; and I do hereby declare the following to be a full, clear, and exact description of the invention, such as will enable others skilled in the art to which it 10 pertains to make and use the same.

My invention has for its object to provide an extremely simple, efficient and low cost so-called "loose leaf file fastener," meaning 15 thereby, a device for binding together a plurality of loose leaves, papers, cards, or other matter; and, to such ends, generally stated, the invention consists of the novel devices and combinations of devices hereinafter 20 described and defined in the claim.

The invention is illustrated in the accompanying drawings wherein like characters indicate like parts throughout the several views.

25 Referring to the drawings,

Figure 1 is a perspective view showing a bundle of loose leaves bound together by one of my improved fasteners, and

Fig. 2 is a perspective view with some 30 parts broken away, showing the overlapped ends of the fastener and the slide for locking together the overlapped ends thereof.

The loose leaves are indicated by the numeral 5. The numeral 6 indicates the 35 binding element, which is preferably a thin narrow metal strip or ribbon bent into rectangular or looped form when completely applied. This strip 6, primarily, is a straight strip and is adapted to be bent 40 into U-shaped form having a span corresponding to the distance between the centers of the perforations 5^a in the leaves 5, so that the ends thereof may be passed through the said perforations and then bent over onto the 45 face of the upper leaf with the ends over-

lapped. The overlapped ends are then secured by a slide 7, which is preferably in the form of a flat loop, of such size that it may be slipped onto the overlapped ends under sufficient friction to prevent accidental sliding 50 movement thereon. When this slide 7 is forced onto the overlapped ends of the binding strip, it will securely hold the same, as shown in Fig. 1.

Preferably, the binding strip 6 is made 55 of pliable sheet metal, which, while having sufficient stiffness to maintain any form in which it is bent, nevertheless, may be readily bent into the desired form, so that its overlapped ends may, as occasions may re- 60 quire, be bent upward into parallel relation for the removal of secured leaves, or the insertion of other leaves, and then be bent back to overlapped form, without breaking.

Obviously, the cost of such fasteners, as 65 shown in Figs. 1 and 2, is very low. Moreover, when applied, they have a very neat appearance and are efficient for the purposes had in view.

What I claim is:—

70 A fastener for loose leaves, papers, cards, or other matter, comprising an integral pliable binding strip adapted to maintain any form in which it be bent, said strip having unbroken parallel edges extending from end to end thereof and adapted to be bent into rectangular looped formation with its ends overlapped and approximately parallel to the body of said strip, and a lock loop made to 75 embrace the overlapped ends of said strip 80 and to move freely thereon, holding the said lapped ends against lateral separation, but free for endwise movements.

In testimony whereof I affix my signature in presence of two witnesses.

WILLIAM C. GOSS.
